DESIGN FOR A CAMERA

Carl H. Whitlock, Lockport, N. Y., assignor to
Norton Laboratories, Portland, Maine, a cor-
poration of Maine

Application October 30, 1933. Serial No. 49,600

Term of patent 14 years

To all whom it may concern:

Be it known that I, CARL H. WHITLOCK, a citizen
of the United States, residing at Lockport,
in the county of Niagara and State of New York,
have invented a new, original, and ornamental
Design for a Camera, of which the following is
a specification, reference being had to the accom-
panying drawing, forming a part thereof.

Fig. 1 is a perspective view of a camera em-
bodying the design;

Fig. 2 is a side elevation thereof; and
Fig. 3 is a front elevation thereof.

The drawing shows the design applied, in the
present instance, to a camera of the non-col-
lapsing type.

I claim:

The ornamental design for a camera, substan-
tially as shown and described.

CARL H. WHITLOCK.
